UNITED STATES PATENT OFFICE.

EDWARD F. GODDARD, OF STRATFORD, CONNECTICUT, ASSIGNOR TO ELECTRIC COMPENSATOR COMPANY, OF NEW YORK, N. Y., A CORPORATION OF NEW JERSEY.

SIDE-KNIFE WIPER.

1,108,357.

Specification of Letters Patent.

Patented Aug. 25, 1914.

Application filed December 13, 1912. Serial No. 736,468.

To all whom it may concern:

Be it known that I, EDWARD F. GODDARD, a citizen of the United States, residing at Stratford, in the county of Fairfield and State of Connecticut, have invented a certain new and useful Improvement in Side-Knife Wipers, of which the following is a full, clear, and exact description.

This invention relates to line casting machines in which the mold moves backward and forward between the casting position and the ejecting position. It is well understood that when the mold is in the ejecting position the slug which has previously been cast in the mold slot is pushed out of said slot and between trimming knives which trim off the surface metal so as to make the slugs of uniform thickness. It is obviously essential that these side trimming knives shall be clean and free from particles of metal adhering to and lying across their cutting edges from previous trimmings. The present invention relates to means whereby these knives are wiped clean of all adhering particles of metal after each slug has been pushed between them and before another slug is pushed between them.

The invention includes a spring actuated knife wiper carried by the movable mold, a sliding cam bar also carried by said mold, and mechanism operated by said cam bar to move and hold the wiper in an inoperative position, and abutments arranged to engage said bar when the mold is near each end of its path of travel, whereby said bar is caused to move endwise relatively to the mold, and thereby in one case to release the wiper to the action of its spring, and in the other case to withdraw the wiper to and hold it in the inoperative position.

The invention is shown in the accompanying drawings and is hereinafter described and pointed out definitely in the appended claims.

In the drawing, Figure 1 is an end view of the side trimming knives and mold equipped with my invention, when the mold is in the casting position. Fig. 2 is a front view of said mold,—the full lines showing the parts in the casting position, and the dotted lines showing the position of some of said parts when the mold is in the ejecting position. In both figures mentioned the part C is broken away. Fig. 3 is a plan view of the mold and knives. Figs. 4 and 5 are fragmentary plan views showing the left end of the mold in horizontal section on line 4—5 on Fig. 1. Fig. 4 shows the relative position of the parts represented when the mold is in the ejecting position; and Fig. 5 shows the same parts when the mold has moved from the ejecting position part of the way toward the casting position. Fig. 6 is a fragmentary plan view showing some of the parts in the positions they occupy when the mold is in the casting position,—the mold being sectioned on line 6—6 on Fig. 1.

Referring to the parts by reference characters M represents the mold, and K and K¹ represent the two trimming knives. These knives are fixed in position and have their edges set at a slight angle to the path of the mold. The mold, after a slug has been cast in its slot, is moved from the casting to the ejecting position, and when it is in this position the mold slot is in such position that the slug therein, when pushed forward, will pass between these trimming knives.

In order to wipe the knives, the mold carries a knife wiper plate A, which is located close to that end of that mold which is adjacent to the ejecting mechanism. It is desirable that this wiper plate shall contact with the knife blades and wipe them while the mold is moving to the ejecting position; and it is also desirable that it shall not contact with said trimming knives when the mold is moving in contrary direction, or otherwise it might deposit on the knives some of the chips and shavings which it had previously wiped off. The knife wiper, which is preferably a brass plate, is arranged in a vertical position with its wiping edge directed forwardly toward the knives. It slides horizontally backward and forward in a guideway between the left end of the mold, and a plate C fixed to said mold. It is under the influence of a spring a tending to push it forward into contact with the knives. Associated with it is a retractor B which is in the shape of a little bell crank lever. This has one downwardly extended arm which engages a pin a¹ which projects sidewise from the wiper plate. The other arm of the latch extends in a substantially horizontal direction and lies in the path of an inclined or cam surface d on the lower face of a bar D which extends entirely through the mold from end to end, and is freely movable therein. It

projects at both ends a little beyond the mold. Just as the mold reaches the ejecting position this bar, by engaging the abutment E, will be moved relatively to the right,—that is to say it will be stopped before the mold comes to rest. This will cause the inclined or cam surface *d* on said bar to engage with the horizontal arm of the bell crank and to rock the bell crank in such direction that its downwardly extended arm, by engaging the pin on the wiper plate, will move said wiper plate rearward so that it cannot contact with the trimming knives. There is a raised flat surface *d*¹ on this bar, onto which the arm will pass when the bar has been moved relatively to the right in the manner and for the purpose stated. Therefore, the wiper plate will be held back out of contact with the knives, while the mold moves to the right toward the casting position. Just as it reaches the casting position the projecting right end of the bar will strike an abutment F whereby the bar is moved relatively to the left in the mold, and this carries the cam or inclined surface *d* relatively to the left, so as to allow the wiper plate to be moved rearward by its spring into that position wherein when the mold moves to the ejecting position it will contact with and wipe clean the trimming knives referred to.

Having described my invention, I claim:

1. In a line casting machine, the combination of side trimming knives, and a mold which is movable in a horizontal path behind said knives between the slug casting and the slug ejecting positions, with a knife wiper movably mounted on the mold adjacent to that end thereof which is directed toward the ejecting position, a spring acting on said wiper to move it forward into operative position, a bar which is movably

mounted on said mold and extends and is movable lengthwise thereof and projects beyond both ends thereof,—said bar having a cam surface, means engageable and movable by said cam surface for moving said wiper in opposition to its spring into an inoperative position, and two abutments located near opposite ends of the path of the mold and in positions to be engaged by the projecting ends of said bar before the mold completes its movement in either direction.

2. In a line casting machine, the combination of side trimming knives, and a mold which is movable in a horizontal path behind said knives between the slug casting and the slug ejecting positions, with a knife wiper movably mounted on the mold adjacent to that end thereof which is directed toward the ejecting position, a spring acting on said wiper to move it forward into operative position, a bar which is movably mounted on said mold and extends and is movable lengthwise thereof and projects beyond both ends thereof, said bar having a cam surface, a bell crank lever pivoted to said mold and having its horizontal arm extended to a position to be engaged by the cam surface on said bar, a laterally projecting shoulder on the wiper with which the nearly vertical arm of said bell crank engages, and two abutments located near opposite ends of the path of the mold and in positions to be engaged by the projecting ends of said bar before the mold completes its movement in either direction.

In testimony whereof, I hereunto affix my signature in the presence of two witnesses.

EDWARD F. GODDARD.

Witnesses:

DAVID PETRI-PALMEDO,
F. P. STILLMAN.
